(57) **CLAIM**

I claim the ornamental design for a light switch with sliding actuator and integrated light source, as shown and described.

DESCRIPTION

FIG. 1 is a prospective view of a light switch with sliding actuator and integrated light source, according to a new design, where the light switch is shown in a closed position. FIG. 2 is a front view of the light switch of FIG. 1.

FIG. 3 is a right side view of the light switch of FIG. 1.

FIG. 4 is a left side view of the light switch of FIG. 1.

FIG. 5 is a top view of the light switch of FIG. 1.

FIG. 6 is a bottom view of the light switch of FIG. 1.

FIG. 7 is a rear view of the light switch of FIG. 1.

FIG. 8 is a prospective view of the light switch of FIG. 1, where the light switch is shown in an open position.

FIG. 9 is a front view of the light switch of FIG. 8.

FIG. 10 is a right side view of the light switch of FIG. 8; and, FIG. 11 is a left side view of the light switch of FIG. 8.
